INVENTOR.

Carl O. Stockman
BY
Ernest D. Jansen
ATTORNEY.

UNITED STATES PATENT OFFICE.

CARL O. STOCKMAN, OF ALBANY, NEW YORK.

PACKAGE TIE.

1,414,599.

Specification of Letters Patent. Patented May 2, 1922.

Application filed September 19, 1921. Serial No. 501,560.

To all whom it may concern:

Be it known that I, CARL O. STOCKMAN, a citizen of the United States of America, residing at Albany, in the county of Albany 5 and State of New York, have invented certain new and useful Improvements in Package Ties, of which the following is a specification.

My invention relates to package ties.

10 For convenience in handling large quantities of paper money, it is the practice to place together a number of bills whose values total a fixed amount and to fasten them together by passing around them a 15 paper band on which is marked the total value of the bills which such band surrounds and pinning it in place. When the bills which are being packaged are those which have been in circulation for a considerable 20 period of time, the possibility of the person performing this work getting a dangerous infection through the accidental scratching or puncturing of the skin on the hands is very great.

25 The object of my present invention is to devise a means for fastening such bands without the use of pins or other metallic parts which might scratch or puncture the skin of the person or persons handling or 30 fastening the same; which will be inexpensive, effective, and easily applied; and which when applied will be sufficiently secure.

I accomplish my objects by means of a band and band fastener made of suitable 35 flexible fibrous material (such as manila paper of suitable thickness) and adapted to be applied and fastened substantially as illustrated in the accompanying drawings, in which:

40 Fig. 1 is a perspective view illustrating the first step in fastening the band about the package.

Fig. 2 is a similar view illustrating the second step.

45 Fig. 3 is a similar view illustrating the third step.

Fig. 4 is a similar view illustrating the finished tie.

50 Fig. 5 is a perspective view of the band fastener.

The same reference characters refer to the same parts throughout the several views.

The method of fastening the band is illustrated in the drawings. As shown in Fig. 1, the first step is to place the band fastener 55 C, over the ends of the band in position about the bundle or package A. The band being drawn snugly about the package, the ends 2 and 3 are then pressed to one side (see Fig. 2) and then turned and inserted 60 beneath the edge of the fastening member C as illustrated in Fig. 3. The ends 4 and 5 of the member C are then bent beneath the band as illustrated in Fig. 4 and the tie is complete. 65

I do not wish to limit myself to the exact shape of band fastener shown in the drawings as the ends thereof may be rounded or pointed, and the slot in the member may be only a slit, none of the material being 70 removed, without departing from the spirit of my invention.

75 My new fastener is easily and quickly applied, when applied as illustrated is sufficiently secure, is inexpensive, and has no metallic parts which might scratch or puncture the skin of persons handling it.

I claim:

1. A package tie comprising a band member of flexible fibrous material having a 80 width many times as great as its thickness; and a fastener member of similar material having a length greater than the width of said band, and a slot longitudinally thereof adapted to pass the ends of said band member. 85

2. A fastener for securing the ends of a band passing around a package, consisting of a piece of flexible fibrous material having a width many times as great as the 90 thickness of the band it is to fasten and a length greater than the width of said band and having a slit therein adapted to pass the ends of the band, the ends of said fastener adapted to be inserted between the 95 band and the package around which it passes.

In testimony whereof I have affixed my signature.

CARL O. STOCKMAN.
